UNITED STATES PATENT OFFICE

MILTON ALDEN, OF SPRINGFIELD, MASSACHUSETTS, ASSIGNOR TO ALDEN MANUFACTURING COMPANY, OF SPRINGFIELD, MASSACHUSETTS, A CORPORATION OF MASSACHUSETTS

VACUUM-TUBE SOCKET

Application filed April 12, 1928. Serial No. 101,311.

The present invention and application is a continuation in part of my copending application, filed February 27, 1923, Ser. No. 621,575, for Socket for vacuum tubes now 5 Patent #1,580,942.

This invention relates to improvements in vacuum tube sockets.

An object of the invention is to provide a device for firmly retaining the vacuum tube 10 of a radio apparatus firmly in its socket and at the same time, to provide good electrical contact between all of the contact members of the socket and the prongs of the tube.

A further object is to retain the vacuum 15 tube on the socket by frictional resistance only which will permit the prongs of the tube to be inserted by moving the tube downward along its axis and to permit its removal in the same way by pulling upward, or in other

20 words it may be defined as a direct push and pull socket, in contradistinction to that type of socket in which a barrel portion is provided with a slot, or groove in the side thereof to receive the pin on the tube, whereby the tube 25 must be rotated slightly in order to lock it in place in the socket.

A further object is in the location, shape and size of the prong receiving openings for insuring flexibility of contact.

30 A further object is to provide a socket for receiving vacuum tubes with pins of varying size and having elongated openings so positioned to provide correct insertion of the tubes.

35 The invention is capable of several modifications yet all embodying the same general features.

Referring to the drawings:

Fig. 1 is a vertical sectional view of one 40 form of socket showing the base portion of a vacuum tube broken away and with the contact prongs inserted in the socket.

Fig. 2 is a modification in which some of 45 the openings in the upper portion of the socket are formed substantially elliptical or elongated, whereby prongs of various sizes and positions on a vacuum tube may be inserted and if necessary slightly rotated, or, in other words, the socket might be defined 50 as universal.

Fig. 3 is a vertical sectional view on the line 3—3 of Fig. 2.

Fig. 4 is a top plan view of a further modification in which the shape of the contact arms are formed with a short bend, and with 55 a depending portion with which portions, the sides of the contact prongs engage.

Fig. 5 is a vertical sectional view on the line 5—5 of Fig. 4 showing the prongs on the tube in contact with the depending portions. 60

Fig. 6 is a sectional view on the line 6—6 of Fig. 7 showing a further modification in which the upper inner end of the contact strip is free to move and when the tube is inserted the strip operates to exert a counter pressure 65 in the opposite direction to that exerted by the pressure of the inserted prong for placing the contact strip under stress for making a good contact.

Fig. 7 is a plan view of Fig. 6. 70

Fig. 8 is a bottom plan view of Fig. 7 omitting one contact spring.

Fig. 9 is a further modification in which the contact strips are folded inward towards each other, and engage opposite sides of the 75 prongs of the tube.

Fig. 10 is a detail view of one of the contact strips with one of the contact prongs about to be inserted.

Fig. 11 is a detail view of a further modification in which the outer surface of the contact strips normally engage a fixed stop. 80

Fig. 12 is a further modification in which the contact strips engage a fixed stop and are under constant stress or tension. 85

Referring to the drawings in detail:

1 designates a socket portion as a whole having the base part 2, the ledge part 3, the upwardly inclined portion 4 and the top part 5 which is formed with openings 6 to receive 90 the prongs 7 of a vacuum tube 8. 9 designates the contact strips which are secured to the base part 2 by means of the threaded bolts 10 and the thumb nuts 11. These strips are formed with a bend at the point 12 intermediate its ends and an upwardly extending portion 13 which normally projects slightly beneath the prong receiving openings 6. The lower ends of the strips are inclined, as shown to fit the under side of the ledge part 100

3. The upwardly extending portion 13 therefore forms a long contact and wiping surface for the prongs 7 of the tube and permits the tube to be inserted by moving it in a direction which coincides with the axial line of the socket and is withdrawn by pulling it upward in this axial line, or in other words it is a push and pull socket, the frictional resistance alone being sufficient to retain the tube in place on the socket.
- Referring to Figs. 2 and 3 the upper top portion 14 of the socket is formed with openings 15 and 16 of elongated or elliptical shaped formation while the openings 17 and 18 are circular and are of different sizes, whereby the prongs 19 of the tube 8, shown in Fig. 3, may be inserted in these openings for making contact with the flexible or elastic contact strips 20 below the openings and even if the prongs of the tube are of different sizes the elongated openings will permit tubes having prongs of different sizes and location to be inserted and slightly rotated if necessary for making contact.
- The arrangement of the contact strips is such that the prongs 19 frictionally engage the same. These contact strips have an upwardly projecting portion 21 and an inwardly extending bent portion 22 which rests against the inner wall 23. When the prongs 19 are inserted the part 21 will yield sufficiently at the point of contact 24 to form a good electrical connection between the strips and the prongs, or, the strips will offer a frictional resistance in the opposite direction to the pressure of the prongs there against. The friction alone being sufficient to hold the tube in place without any other locking devices.
- It should be stated that the ledge portion 25, see Fig. 2, has marked thereon, the words "Pin here" and an arrow as indicated at 26. This is for the purpose of properly locating the tube on the socket in order to prevent the filament of the tube from being burned out in case a wrong connection with the battery terminals is made.
- Figs. 4 and 5 are for a modification in which the contact strips 27 are formed with a short bend 28 at their upper inner ends and a short depending part 29 with which the tube prongs 30 engage when inserted. This construction affords a long yieldable arm part 31 together with the short contact part 29.
- Figs. 6, 7, and 8 are for a further modification in which the base part 32 is recessed as shown. This construction is formed with the top portion 33 having the openings 33' to receive the prongs 34 of the tube as before. 35 is an annular recess at the upper end portion of the recess which is for strengthening purposes. If desired the part 43 may engage the boss when the tube is inserted. 36 is a depending or boss portion. 37 are the contact strips which are attached at their

lower ends to the base portion 32 by means of the small screws 38 and nuts 39. The inner ends of the contact strips 37 are bent at 40 and then extend upward at 41, their upper ends terminating in the reversely bent tips 43. When the prongs 34 are inserted in the openings 33' they will slide down and on the outer surfaces 45 of the strips. This operation will place still further stress on these strips in a lateral direction which may be indicated by the dotted lines 45'. The tubes will therefore be firmly retained in place on the socket, by friction alone. 47 are the securing screws for the strips 37. The strips must yield laterally when the prongs 34 are inserted. The strips therefore make good electrical contact at all times both during the insertion and removal of the prongs because of the constant stress which is imparted to the strips. 37' designate the usual openings to receive the attaching screws.

In Fig. 10 the contact strip 48 is formed with two struck up portions 49 and 50 having the downwardly inturned ends 51 and 52 which, as shown, do not quite meet. The prongs 53 when inserted make contact with these inturned portions and on opposite sides of the same whereby a double contact is made. This construction is such that the tube is retained in place by friction alone. In all of these forms of sockets the tube is understood as being retained in place by friction alone yet permitting it to be readily inserted and removed.

Referring to Fig. 11, the contact strips 54 are under a bending stress at all times since they are so shaped or bent when formed as to normally exert a pressure on the shoulders 55 formed in the sides of the openings for the prongs as shown in this figure. When the prongs 56 of the vacuum tube are inserted they will engage the downwardly extending part 57 and place still greater stress on the contact strips. These strips are therefore under stress at all times and whether or not a tube is inserted.

Fig. 12 illustrates a modification in which the contact strips 58 are so shaped, or bent, when formed, that the curved part 59 normally engages the shoulder 60 which extends into and terminates at the prong receiving openings 61, or in other words, the curved part 59 extends across the openings 61, whereby, when the prongs 62 are inserted they will engage the outer surface 60 and move them inward against the tension or set of the strips. A comparison of the two positions of the strips in Fig. 12 clearly illustrates the idea that these strips are normally under stress or tension when attached to the base piece by the bolts 63'. Friction alone operates to retain the tubes in place.

One of the advantages of my improvement is that it is capable of receiving and holding

tubes having short prongs or contact terminals.

The socket, as shown in Fig. 2 illustrates elongated openings of different sizes for receiving contact prongs or pins of different sizes and location. This is important as different types of vacuum tubes have different sizes and positions of contact pins.

It is to be understood that the present socket construction is designed to receive vacuum tubes having comparatively short or long prongs or pins as well as pins of varying diameters and location as regards to center. The dimensions in the drawings are illustrative and not drawn to scale.

What I claim is:

1. A vacuum tube socket comprising an insulating base having a perforated top with a depending wall, an outwardly extending flange and a supporting edge and having a chamber enclosed by said parts, the lower wall of said flange being inclined relative to the top and conducting members each formed of a single strip of spring metal bent intermediate its ends and having its outer end secured to said inclined lower wall of said flange and its opposite end extending upwardly and adjacent the lower edge of one of the perforations in the top.

2. A vacuum tube socket comprising an insulating base having a perforated top with a depending wall, and an outwardly and downwardly extending flange, and having a chamber enclosed by said parts, and conducting members each formed of a single strip of spring metal bent intermediate its ends and having an outer spring arm secured to a lower wall of said flange and an inner spring end extending inclined upwardly and adjacent the lower edge of one of the perforations in the top.

3. A vacuum tube socket comprising an insulating base having a top with a number of perforations of different sizes and a depending wall and an outwardly and downwardly extending flange and having a chamber enclosed thereby, a lower wall of said flange being arranged below the top and conducting members each formed of a single strip of spring metal bent upwardly intermediate its ends and having its lower and outer end secured to said lower wall of said flange and its upper and inner contact end extending upwardly adjacent the lower edge of one of the perforations in the top with a yielding contact surface in position to be engaged by a side wall of a tube prong, said contact ends being adapted to coact with prongs of different diameters and to yield independently of each other.

4. A vacuum tube socket comprising an insulating base having a top with four perforations and a depending wall and an outwardly and downwardly extending flange and having a chamber enclosed by said parts, a lower

wall of said flange being arranged below the top and conducting members each formed of a single strip of spring metal bent upwardly intermediate its ends and having its lower and outer end secured to said lower wall of said flange and its upper and inner end extending upwardly adjacent the lower edge of one of the perforations in the top.
